UNITED STATES PATENT OFFICE.

HARRY FRANKLIN PERKINS, OF PORT ARTHUR, TEXAS.

PROCESS OF DISTILLATION.

Application filed January 17, 1922. Serial No. 529,862.

To all whom it may concern:

Be it known that I, HARRY F. PERKINS, a citizen of the United States, residing at Port Arthur, in the county of Jefferson and State of Texas, have invented certain new and useful Improvements in Processes of Distillation, of which the following is a specification.

This invention relates to processes of distillation; and it comprises a method of distillation particularly adapted to petroleum products, although useful in other relations, wherein vapors coming from a suitable still are passed successively through two or more equilibrating zones of controlled temperature, each successive zone differing from its predecessor slightly in temperature and each being kept at substantially uniform temperature throughout its length and throughout its width, and are then condensed; and it also comprises as a new combination of apparatus elements, a suitable still and a suitable condenser with a plurality of jacketed casings acting as temperature stabilizing means located between the vapor outlet of the still and said condenser, each casing being provided interiorly with a heat-conductive packing of metallic nature; all as more fully hereinafter set forth and as claimed.

As is well known, petroleum oils are mixtures of a great number of different oily hydrocarbons, many of which differ from each other very slightly in composition, boiling point and other characteristics. In any petroleum oil there are oily hydrocarbons, or groups of hydrocarbons, of widely separated boiling points, but there are also hydrocarbons of intermediate boiling points; and for this reason, under the well known laws governing volatilization of miscible liquids, it is substantially impossible on a commercial scale, or even in a laboratory way, to separate any one of these individual hydrocarbons by distillation, or even to separate them in any sharply marked groups. The boiling points of the hydrocarbons of the composite mass are so inter-linked by the presence of the intermediate hydrocarbons as to preclude sharp separations. The ordinary fractionating columns, constant temperature stillheads, etc., adapted for the separation of two or a few components do not here give clean cut, definite fractions. In commercial refinery practices,

petroleum hydrocarbons are distilled, so to speak, in groups; the crude oil is distilled with steadily rising temperature to give a few fractions or cuts; and these cuts are then generally redistilled to give new cuts 20 boiling within certain temperature limits—gasoline, kerosene, etc. The cuts however always, so to speak, overlap; the kerosene contains oils which might usefully be contained in the gasoline cut and vice versa. 65

It is an object of the present invention to provide a method of distillation which will give at once cuts of more definite and homogeneous nature than those afforded by the usual methods and with such a distribution 70 of the various hydrocarbons as will give a large volume of the desired cuts. In so doing, it is necessary to pay careful attention to the details of the operation and this is done in the present invention. 75

At any point in a refluxing partial condenser handling petroleum vapors, whether an ordinary runback, a "constant temperature stillhead" or a fractionating column, liquid and vapor are in contact and striving to come to an equilibrium at the local temperature. Attainment of equilibrium is not instantaneous. The liquid is (or should be) that which will just condense at this temperature; the vapor that which will just 85 not condense. The position of the equilibrium is quite sensitive to minute temperature changes; and since the vapor readily dissolves in the liquid with evolution of heat, or re-evaporates with absorption of 90 heat, according to the composition of the vapor phase, the equilibrium point is constantly shifting. With any shift in the equilibrium, the volume of vapor and that of liquid undergo reciprocal changes. In 95 order to secure and fix an equilibrium, time is required; and it is necessary to give a large area of contact between vapor and liquid in a constant temperature zone of suitable size. 100

In the present invention in order to fix and maintain the equilibrium the vapors prior to going to a condenser are sent through a plurality of constant temperature zones of suitable length with merely a slight difference in temperature between adjacent zones. At least two are used; and more may be employed with advantage. In each zone conditions are maintained so that the equilibrium itself can be relied upon to establish 110

and maintain the specific temperature desired; the desired final equilibrium being approached in the zone next before the last and finally definitely set in the last zone. It is desirable that the temperature drop between zones shall be small but definite. A temperature drop results in condensation with liberation of heat; an effect of course opposing the temperature drop and in order to secure the result I want as well as to obviate the disturbing effects of air cooling I employ a circulation of liquid which may be at a temperature slightly below that of the equilibrium desired. The temperature differential should not be great, the function of the circulated liquid being rather to carry off heat units liberated in condensation and act as a sort of thermal safeguard than to act as a cooling medium in the sense of lowering the temperature. Distillation conditions are so adjusted as to have the vapors enter the final zone at nearly the temperature therein prevailing, allowing final adjustment and establishment of equilibrium to take place in the zone itself. Any sudden or violent cooling within the zone, with the attendant copious condensation whether due to air cooling or cooling by circulating liquid would defeat my purpose. I customarily use the temperature regulating liquid in a jacket surrounding the zone. Its temperature being very nearly that in the zone itself it obviates practically any influence of the air temperature and is, to that extent a sort of thermal insulating means.

In commercial specifications of volatile petroleum oils, it is customary to specify the overpoint, or the point at which the first drop distils over and the end point, or the point where all the oil is volatilized. In practicing the present invention in distilling petroleum oils to make any particular product, such as gasoline or kerosene the last of the constant temperature zones is maintained as nearly as possible at the end point of the cut to be made; say within 4 or 6 degrees F. above or below, and the next to the last zone at a temperature just above that in the last zone. In the next to the last zone it is the object to set an equilibrium with a little more of the higher boiling oils in the vapor phase than are desired in the final condensate to be made, thereby securing vapors richer in low boiling oils, and then take out this excess of high boiling oil in the last zone. To aid in preserving even or equalized temperature within each zone it is as stated jacketed for circulating a temperature-controlling fluid, such as water, oil or steam. Coils may be used but the jacket is desirable. And in order to obviate as much as possible local internal temperature differentials which would interfere with the equilibrium each zone is provided with a packing of some

metal with good heat conductivity. The internal temperature should not differ more than, say, 10° F. between any two points; as for example, between periphery and center in any horizontal plane. Iron, copper or nickel may be used. The metal packing not only provides for transverse and longitudinal equalization of temperature but gives a large area contact between vapors and liquids with the mass of liquid trickling over the metal comparatively small as compared with the mass of such metal. The mass of metal acts as heat-stabilizing means. The packing may be of any shape or arrangement giving good thermal conductivity across the zone with ample contact between liquid and vapor and not too much friction to oppose passage of vapor. Balls, pellets, disks, rings etc. may be used. Balls of nickel or copper may be used. "Steel wool" makes a good packing but for large apparatus metal of coarser cross-section is better. Where flat disks, rings, etc. are used, it is desirable that the packing have at least some of the horizontal surfaces slightly inclined, say about 1 degree. The packing should be such as to give a free vapor path of somewhere between 0.1 and 0.2 square inch per gallon per hour capacity; the free path being somewhat greater at the entrance than at the exit end of each constant temperature zone. I do not desire that any vapor be more than, say, three-thirty seconds of an inch away from a surface of heat-conductive metal and the packing should be suitably constructed or arranged to give this result. The speed of passage of the vapors through the zone may be around 250 feet per minute.

Operating in the manner just described, vapors are first brought to equilibrium with liquid condensed therefrom (and the liquid, of course, with the vapors) at a temperature just above the end point desired, the condensed liquid draining away and the vapors being left with a little more high boiling component than is desired in the final condensate. The vapors are then again brought to equilibrium at a lower temperature with their condensate at the end point desired. After establishment of equilibrium, the equilibrated vapors are sent to the usual type of condensers and condensed to give the cut desired. The result is the production of a comparatively large volume of the product desired and of a cut which is more homogeneous than usual. In making a distillate marketable as gasoline under the present invention, good merchantable gasoline may be directly distilled from crude oil in quick operation and the volume of merchantable gasoline thus obtained is greater than that made in other ways even with repeated distillations.

In the continuous distillation of crude oil,

the oil is sometimes passed from end to end of a long horizontal cylindrical still, vapors being taken off at a plurality of points along the length and sent up through de-phlegmating towers to give successive cuts. In this invention the successive vapor off-takes are provided with equilibrizing zones of the described character, each being maintained under conditions to make one particular cut, or several groups of zones in series may be used in one vapor outlet to give desired cuts.

I have so far described the application of my invention only to distillation cuts made without the aid of steam. The process, however, may be applied also to cuts made by distillation with open steam or gas such as hydrogen. In so doing, however, the temperature maintained in the last equilibrating zone is the end point of the desired fraction in distilling under a vacuum, or reduced pressure equivalent to the proportion of steam or gases in the vapors in making the cut. Water, of course, is a body boiling at a much lower temperature than the cuts which are made with the aid of steam distillation and the presence or absence of water vapor in the vapor under treatment in the equilibrating zone makes no difference in obtaining the desired type of equilibrium.

In the accompanying illustration I have shown, more or less diagrammatically, certain apparatus within the described invention and capable of use in the performance of the stated process. In this showing the figure is a view, partly in elevation and partly in section, of a suitable apparatus. Details of condensing means, firing means, etc., have been omitted.

In this showing, 1 is a conventional representation of a furnace chamber provided with suitable firing means, waste gas outlets, etc., (not shown) and 2 is a conventional showing of one end of an ordinary cylindrical still mounted therein. This still may be one of the stated continuous type stills having a plurality of successive vapor off-takes along its length. Vapors leave the still through vapor outlet 3, having the usual sloping runback portion 4. The vapors pass successively through a plurality of zones. Two, A and B, are shown, but more may be employed. As shown, A is composed of an inner steel or iron casing 5, provided with temperature maintaining jacket 6 having an inlet 7 and outlet 8 for a suitable fluid of suitable temperature, such as steam, oil, hot water, etc. Within, this casing is provided with a metallic packing 9. As shown, this packing is composed of metal disks in staggered horizontal arrangement. The disks may be circular, hexagonal, octagonal, square, etc. As shown, the disks are somewhat thicker on one side than the

other, giving a section which is, so to speak, of truncated wedge shape; the inclination from the horizontal arrangement of the side, however, being very small—usually not over 1°. At the bottom of the zone the disks are placed in somewhat opener arrangement than at the top giving a somewhat greater cross-sectional area of free passage for vapor. At the bottom, zone A, as shown, is provided with reflux connections 10 leading condensate back into the still. As a rule the condensed oils are sent back to the still though they may of course be directed elsewhere. It is best to carry the refluxed liquid through conduit 11 to a point near the bottom of the still. Zone A at its top opens into B, giving opportunity for unrestricted passage of vapors from A into B. B is provided with an individual jacket 12 having supply 13 and outlet 14 for a temperature maintaining fluid. In B, as in A, occurs the metal packing 9, the packing as shown being continuous through A and B. Purified vapors leave B through vapor outlet 15, leading to a suitable condenser, not shown. The temperature controlling fluid may pass as shown from the outlet of the jacket of B to the inlet of the jacket of A by suitable connections.

In certain cases, the jacket of one of these sections may be omitted and air cooling relied upon, but this I do not recommend.

In use of this apparatus, presuming that a gasoline cut with an end boiling point of, say, 410° F. is to be obtained from crude oil, still 2 is charged with the crude oil and firing resorted to in the usual way. Zone B is then kept at its top at about 410° F., or within the stated limits of tolerance, and zone A at a temperature 4 or 5 degrees F. higher. Under these conditions distillation with the production of grouped hydrocarbons in clearly cut groups becomes very efficient and a larger yield than usual of a gasoline with the desired end point is obtained. Instead of using crude oil, naturally, a distillate, such as naphtha or other oil mixtures may be used in 2. The apparatus may be used in exactly the same way for giving large yields of uniform kerosene or of any other usual fraction or cut.

While I have designed this invention more particularly for use with petroleum oil and other mineral oils, such as the shale oils, it may be of course used in other connections, as in obtaining fractions of coal tar of greater uniformity with fewer distillations than is usual.

What I claim is:—

1. In the distillation of fractions or "cuts" of petroleum oils the process which comprises producing vapors of the oils to be distilled, transmitting said vapors in a tortuous pathway through a metallic packing of material freely conducting heat and posi-

tively maintained at the temperature near but somewhat above the end point of the cut to be made, then through a similar device maintained at a temperature within 5 degrees Fahrenheit of the end point of the cut to be made and finally condensing residual vapors to afford such cut.

2. In the process of claim 1, the method which consists in positively controlling the 10 temperature in each body of packing within 10 degrees Fahrenheit as a maximum difference between any two points in such body.

3. In the process of claim 1, the improvement which comprises transmitting said 15 vapors in said tortuous pathway at a distance not greater at any point than about

three thirty-seconds of an inch from said metallic packing.

4. In the process of claim 1, the improvement which comprises transmitting said vapors through a tortuous pathway of somewhat larger cross section at the entrance end than at the exit end.

5. In the process of claim 1, the improvement which comprises giving a free total vapor path to the material having a cross-sectional area amounting to between one-tenth square inch and two-tenths square inch per gallon of distillate delivered per 30 hour.

In testimony whereof, I have hereunto affixed my signature.

HARRY FRANKLIN PERKINS.
